UNITED STATES PATENT OFFICE.

CHARLES L. CARLSSON, OF IVORYTON, CONNECTICUT.

RAIL JOINT AND BOND.

1,383,074.

Specification of Letters Patent. Patented June 28, 1921.

Application filed August 13, 1919. Serial No. 317,261.

To all whom it may concern:

Be it known that I, CHARLES L. CARLSSON, a citizen of the United States, residing at Ivoryton, in the county of Middlesex and State of Connecticut, have invented certain new and useful Improvements in Rail Joints and Bonds, of which the following is a specification.

This invention relates to an improved rail joint and bond and has as one of its principal objects to provide a joint which will reduce pounding of the rail ends.

The invention has as a further object to provide a joint which will reduce wear upon the rail ends as well as wear upon the wheels of rolling stock.

A further object of the invention is to provide a joint wherein an effective electrical connection will be formed between the rail ends.

And a still further object of the invention is to provide a joint employing a rigid bond coupling but wherein vertical and lateral movement of the rail ends relative to each other cannot serve to molest electrical connection between the rails.

Other and incidental objects will appear hereinafter. In the drawings:

Figure 1 is a fragmentary plan view of my improved joint,

Fig. 2 is a side elevation of the joint,

Fig. 3 is a transverse sectional view, the rail bond being removed, and

Fig. 4 is a fragmentary horizontal sectional view particularly illustrating the rail bond.

Referring now more particularly to the drawings, meeting rails are indicated at 10 and 11 respectively. At their adjacent ends, each rail tread is cut away at opposite sides thereof to provide notches 12 and 13 respectively, the notch 12 being somewhat shorter than the notch 13 and, as will be observed, the notch 12 in each rail tread registers with the notch 13 in the other rail tread. Consequently, the recesses thus formed are staggered with respect to each other and preferably said notches are formed with beveled end walls. Between the registering notches 12 and 13 are defined alined tongues 14, these tongues being in reality a continuation of the rail webs and at their upper edges forming a continuation of the tread surface of the rails.

Coacting with the end portions of the rails are fish plates 15 notched at their outer

edges to receive spikes in the usual manner. These fish plates are, as particularly illustrated in Fig. 3, provided with base flanges 16 which extend beneath the rail ends while the vertical flanges 17 of said plates lie in spaced relation to the rail webs at opposite sides thereof. Formed on the flanges 17 at points substantially midway between the ends of the plates are tread blocks 18 rising from the upper edges of said flanges. These tread blocks are received within the recesses formed by the registering notches 12 and 13 at the rail ends and are shaped to conform to the contour of the treads of the rails so as to provide a continuation thereof. As best illustrated in Fig. 1, the tread blocks 18 are provided with beveled ends lying in spaced parallel relation to the beveled end walls of said notches. Extending through the flanges 17 of the fish plates and through the rail webs are spaced bolts 19 securing the fish plates in position and connecting the rail ends. As will be seen, these bolts will serve to rigidly clamp the tread blocks 18 against the tongues 14 at the ends of the rails so that a firm connection will be formed between the rails and a smooth tread surface presented to the wheels of rolling stock passing over the rails. Furthermore, as will be noted, ample space is provided between the tread blocks and the end walls of the notches 12 and 13 to compensate for expansion and contraction of the rails and the rail ends are similarly slightly spaced apart. In this connection particular attention is directed to the fact that in providing the tongues 14 but a relatively short gap is formed between the ends of these tongues at the tread surface of the rails and this gap is located centrally of said surface and between the tread blocks 18. Consequently, these tread blocks will support the wheels of rolling stock to pass over said gap without pounding against the rail ends or wear of the wheels. I accordingly provide a very effective type of rail joint.

Formed through each of the flanges 17 of the fish plates is a pair of openings 20 lying at opposite sides of the joint between the rails. Opposite these openings, contacts 21 are secured to the rail webs and at their opposite corresponding ends these contacts are formed with flat heads 22. The contacts are preferably non-corrosive and may be constructed of any approved material. Mounted upon the flange 17 of one of the fish

plates is a bonding yoke 23 provided with parallel bosses or arms 24 snugly fitting within the openings 20 of said plates. The arms are hollow and are formed at their inner ends with substantially hemispherical contact seats 25 having concavo convex bottom walls 26 through which are formed openings 27. Formed to fit the seats 25 are substantially hemispherical contacts 28 loosely connected with the arms by fastening devices 29 extending freely through the openings 27 so that the contacts may rock within said seats. The fastening devices 29 will, of course, prevent accidental loss of the contacts when the yoke 23 is detached. Removably fitted through the flange 17 of the plate from the inner side of said flange to engage at its inner end with said flange is a stud bolt 30. In this connection, it should be observed that the flanges of both of the plates are each provided with a pair of the openings 20 and are also formed with an intermediate opening to receive the bolt 30 so that the fish plates are thus made interchangeable. Threaded upon the outer end portion of this bolt is a nut 31 and surrounding the bolt to bear between said nut and the yoke is a spring 32 acting against the yoke to constantly and forcibly urge the flat faces of the contacts 28 into engagement with the adjacent flat heads 22 of the contacts 21. Effective electrical connection between the

rails will thus be provided and in this connection it is to be particularly observed that since the contacts 28 are mounted to rock 35 within their seats 25, relative vertical or lateral movement of the rail ends cannot serve to break the electrical contact between the elements 22 and 28 since the latter elements will shift to compensate for such movement 40 of the rail ends. The rails will thus always be effectively bonded.

Having thus described the invention, what is claimed as new is:

In a rail joint, rails each having a tread 45 portion provided at one side with a notch and at the opposite side with a longer notch, the notches having correspondingly beveled end walls and the long notch of each rail facing the short notch of the other rail to define 50 recesses at opposite sides of the rails, and fish plates connecting the rails and having base flanges engaging therebeneath, the fish plates having vertical flanges confronting the rail webs in spaced relation thereto and being 55 formed medially of the plates with upstanding tread blocks fitting in said recesses providing a continuation of the rail treads and having beveled ends confronting the beveled end walls of the recesses in spaced parallel 60 relation.

In testimony whereof I affix my signature.

CHARLES L. CARLSSON. [L. S.]
